US00D823290S

(12) **United States Design Patent** (10) **Patent No.:** **US D823,290 S**
(45) **Date of Patent:** **** Jul. 17, 2018**

(54) **CASE FOR ELECTRONIC DEVICES**

- (71) Applicants: **Dae-Young Kim**, Seoul (KR); **Soo Ha Jung**, Seoul (KR)
- (72) Inventors: **Dae-Young Kim**, Seoul (KR); **Soo Ha Jung**, Seoul (KR)
- (73) Assignee: **SPIGEN KOREA CO., LTD.**, Bongeunsa-ro, Gangnam-gu, Seoul (KR)
- (**) Term: **14 Years**
- (21) Appl. No.: **29/518,391**
- (22) Filed: **Feb. 23, 2015**
- (51) LOC (11) Cl. **14-03**
- (52) U.S. Cl. **USPC D14/250**
- (58) **Field of Classification Search**

(57) **CLAIM**

The ornamental design for a case for electronic devices, as shown and described.

DESCRIPTION

FIG. 1 is a front perspective view of a case for electronic devices showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front perspective view of the inner shell of the case;

FIG. 10 is a rear perspective view of the inner shell of the case;

FIG. 11 is a front perspective view of the outer frame of the case;

FIG. 12 is a rear perspective view of the outer frame of the case;

FIG. 13 is an exploded front perspective view thereof; and, FIG. 14 is an exploded rear perspective view thereof.

The broken line in the figure drawings represents unclaimed environment only and forms no part of the claimed design.

1 Claim, 14 Drawing Sheets
